FLATIRON

William J. Russell, New Britain, Conn., assignor
to Landers, Frary & Clark, New Britain, Conn.,
a corporation of Connecticut

Application May 10, 1950, Serial No. 161,127

1 Claim. (Cl. 38—74)

1

The present invention relates to an electric flatiron and more particularly to an electric flatiron of novel construction having many unexpected advantages from a use standpoint, particularly in respect to the marked decrease in fatigue which is experienced by a user of the flatiron of this invention as compared with the fatigue normally resulting from the use of conventional flatirons.

The use of electric flatirons normally requires a substantial expenditure of effort, is time consuming, and generally entails a certain degree of concentration on the part of the operator to be sure that the ironing movements employed produce satisfactory results and utilize to the fullest extent possible the capabilities of the flatiron employed. This results in an alarming degree of fatigue on the part of the operator which renders ironing one of the most difficult and tiresome of household chores.

A basic object of the present invention is to provide an electric flatiron which makes it relatively easy to iron, both from the standpoint of readily measurable factors, such as the amount of time required to complete a given work load, and also from the standpoint of more difficultly measured but probably more important factors such as reduction in tension and fatigue experienced by the user.

A more specific object of the invention is to provide an electric flatiron which permits the use of less fatiguing ironing technique, such as by permitting the user to employ easy natural strokes in operating the iron without loss of ironing efficiency and by allowing the operator to effectively handle interruptions in the surface being ironed, such as, pleats, buttons, loops, and the like, without limitation to specific stylized manipulations of the iron.

Another specific object of the present invention is to provide an electric flatiron of the character referred to which has a considerably larger ironing surface than that normally present in conventional irons and yet which does not suffer a disadvantage from a weight standpoint; in fact, by keeping within the preferred weight limits of a conventional flatiron there results a lesser weight and consequently lesser frictional resistance to ironing movement per unit of soleplate area. Included in this object is the aim of providing a larger ironing surface which is compactly arranged so as to avoid excessive dimensions and to provide an iron which is balanced and not awkward either in appearance or in use.

A further object of the invention is to provide a flatiron of the character referred to which is

2

easier to control during ironing in that the position of the iron and, particularly, the periphery thereof is visible over a wide angle of view and the travel of the iron can be accurately observed, even though sweeping strokes are employed, without the need for excessive body movement on the part of the operator.

Other objects will be in part obvious and in part pointed out more in detail hereinafter.

10 The invention accordingly consists in the features of construction, combination of elements, and arrangement of parts which will be exemplified in the construction hereafter set forth and the scope of the application of which will be indicated in the appended claim.

In the drawings—

Figure 1 is a side view of a completely assembled electric flatiron embodying the present invention.

20 Figure 2 is a longitudinal cross-sectional view of the soleplate of the iron.

Figure 3 is a plan view of the completely assembled iron shown in Figure 1.

25 Figure 4 is a transverse cross-sectional view of the soleplate; and

Figure 5 is a diagrammatic plan view of the soleplate showing the manner in which the boundaries thereof are determined.

30 As mentioned above, it is a principal object of the present invention to provide an electric flatiron which is notable for the way in which it reduces fatigue on the part of the user, and the novel construction of the flatiron of the present invention has been discovered for attaining this aim without regard to any existing theories of flatiron design and construction, most of which are effective in theory only and when reduced to practice do not actually enhance the operation of the iron. The invention of the applicant's

35 novel construction is borne out by the fact that extensive tests have proved that an average operator provided with the flatiron of the present invention can effect a saving of as high as 50% in the time required to complete a given ironing load, as compared with that required when using conventional irons, and experiences a very distinct relief from fatigue and tensions. Various theories might be advanced to explain the greatly unexpected and superior results obtained by the 40 use of the flatiron of the present invention but it is not desired to rely on any such theories and the following description will be directed specifically to a definition of the actual embodiment of the invention.

55 Referring to Figure 1 of the drawings, it will be seen that the electric flatiron of the present

invention is partly conventional, in that it includes a soleplate 10, a shell or cover 20 resting on the upper surface of the soleplate for enclosing the electrical connections, thermostat, etc. (not shown), and a super-deck 30 mounted on the top of the shell and provided with a handle 40. As best shown in Figure 3 of the drawings, the super-deck 30 and handle 40 are disposed somewhat to the rear of the iron and a portion of the super-deck indicated at 31 actually overhangs the rear portion or heel of the iron. This construction not only gives the iron a stream-lined appearance but also permits the iron to be stood on end when not in use, the iron resting on the rear edges of the super-deck and handle. The shell 20 has an outer periphery 21 conforming generally to the periphery 11 of the upper surface 12 of the soleplate 10 so as to provide a smooth substantially continuous side surface on the iron.

As best shown in Figures 3 and 5 of the drawings, the soleplate 10 has an outer periphery 13 which is generally teardrop shaped. Referring to the diagrammatic view of Figure 5, it will be seen that the periphery 13 is actually a substantially continuous curve formed by three parti-circular portions indicated at 14, 15 and 16, respectively. The parti-circular portion 14 is substantially a semi-circle, the completed circle being indicated for purposes of illustration by dot and dash lines A and the center being indicated at B. The portion of the periphery indicated by reference numeral 15 is a portion of a much larger circle indicated partially by the dot and dash line C having a center D disposed on an extension of the minor axis (point of greatest width) of the soleplate 10 indicated by dot and dash line E. Similarly, the portion of the periphery indicated at 16 is formed by a substantially equal circle shown partially by dash and dot line F and having a center (not shown) which is similar to the center D but disposed at the opposite side of the soleplate. I have found that an important factor in obtaining the improved and unexpected results of the iron of the present invention is to construct the circles C and F with a radius approximately three times that of the circle A. The intersection of the parti-cylindrical edge portions 15 and 16, which is indicated at 17, forms the point or toe of the iron and the angle of intersection is approximately 90 degrees.

The point 17 may also be determined by the intersection of two lines indicated by dot and dash lines G and H, which lines G and H intersect at an angle of approximately 45 degrees and are drawn tangential to the circle A. The overall length of the soleplate is approximately 75% greater than the maximum width as measured along line E.

It has been found that an iron provided with a soleplate formed in accordance with the invention and having a periphery defined as set forth above can be freely moved over a surface to be ironed in any direction with equally desirable results, such as, freedom from wrinkling, and the ironing operation, therefore, is not limited to movements substantially in the direction of the long axis of the soleplate. As a consequence, the operator may move the iron in free sweeping strokes using natural arm movements in whatever direction will most quickly cover the surface being ironed and without any concern as to whether good ironing results will be obtained. Furthermore, since deviation from any fixed course of movement does not produce poor results, the op-

erator rarely has to go over the same surface twice. In the use of conventional irons the operator normally moves the iron mainly by bending the elbow, thereby producing a linear reciprocating ironing motion. When the iron of the present invention is utilized, however, it is possible to swing the entire arm in a sweeping curved motion without materially bending the elbow, which greatly increases the area of ironing surface which is covered by an ironing stroke, and also permits the user to employ the larger arm muscles with a consequent decrease in strain and fatigue.

While one of the important characteristics of the flatiron of the present invention is the manner in which the periphery of the soleplate is formed, as described above, the advantages of this construction from the standpoint of providing a flatiron which will be effective for markedly reducing fatigue can be fully realized only by the use thereof in conjunction with a second important feature of the flatiron of my invention, which is a unique small angle bevel, formed by inclining the edge portions of the soleplate at a critically small angle. The bevel of the soleplate is best shown in the cross-sectional views of Figures 2 and 4 of the drawings, and gives the soleplate a flared, skirt-like appearance. In the specific embodiment, the angle of bevel is 39 degrees to the plane of the soleplate except at the toe 17 where the intersection or joinder of curved peripheral portions 15 and 16 produces a bevel at the point which is at an angle of approximately 30 degrees. In general, it is desired to provide the soleplate of the electric flatiron of the present invention with a bevel such that the peripheral surface of the soleplate is at an angle to the plane of the soleplate within the range of 30 to 40 degrees.

An important advantage of such a small angle bevel for the soleplate, it has been discovered, is that it permits any peripheral portion of the soleplate to be used for ironing around buttons, pleats, and the like, the extremities being sufficiently thin at all points to be inserted underneath the button, or fold of cloth, etc., from any approach. Inasmuch as the iron can be moved in any direction with good ironing results and will be so operated by a skillful user, the ability to handle interruptions in the surface being ironed from any approach is an important factor in eliminating waste motion such as is caused if only a particular limited notched portion of the soleplate, for example, could be utilized for this purpose. It has been observed in accordance with the present invention, that it is possible to form a soleplate with a bevel in the range of 30 to 40 degrees as described and still obtain good heat transfer to the periphery of the iron so that the usefulness and efficiency of the marginal portions of the iron is not impaired and this critically small angle is just sufficient to render it possible for the operator to extend the soleplate under a button or pleat, or the like, from any direction and as a continuation of a regular ironing stroke as above described. There is thus eliminated the need for excessive use of and reliance upon the toe portion of the iron which frequently causes the operator to place excessive force on the toe of the iron and actually partially lift the remaining portion of the soleplate from the surface being ironed. Such inefficient use of the flatiron may be entirely avoided by the use of the present invention.

A further advantage of the use of a small angle bevel extending around the edge portions of the soleplate together with the manner in which the edge portions are curved as above defined, is that the ironing surface or area of the iron may be increased to at least 50% over that of conventional irons of equivalent weight. In a commercial embodiment of the present invention utilizing readily available materials there is provided a bottom ironing surface of 34 square inches in an iron weighing only 3 1/4 pounds, this being well within the weight range of 3 to 3 1/2 pounds which is found to be preferable for good ironing results, while at the same time requiring a minimum effort on the part of the operator. In the commercial embodiment referred to, the diameter of the circle A (of Fig. 5) is 5 1/8 inches which results in a soleplate having a maximum width of 5 1/8 inches and a length of 9 1/4 inches.

As best shown in Figures 3 and 4 of the drawings, the enlarged ironing surface provided by the soleplate 10 and the small angle bevel extending around the edge portions of the soleplate together with the shape of the soleplate renders the periphery of the soleplate easily viewable at all times by the operator when in the normal operating position, and the periphery is not obscured in any way by the super-structure and handle or by the hand of the operator. This permits the operator to follow the movements of the iron throughout without shifting body position and also makes it possible to utilize more efficiently the particular portion of the periphery of the iron desired for ironing around buttons, and the like, without need for changing the direction of the iron, i. e., the position in which the iron happens to be moved into contact with the button, pleat, or the like.

It will be noted by reference to Figures 3 and 4 of the drawing that the formation of the bevel at a small angle renders the bevel much wider for a given thickness of soleplate both in the plane of the bevel and in plan view which creates an optical illusion that the soleplate is smaller in area and thinner than it actually is and enhances the stream-lined appearance of the iron. In the commercial embodiment of the invention the soleplate adjacent to the beveled edge is approximately 1/2 inch in thickness, thus creating a bevel which is 3/4 inches wide. The use of a wide bevel also has an advantageous effect upon the balance of the iron rendering the iron easier to handle and stand on end.

The manner in which the soleplate is secured to the remainder of the iron is not shown in detail in the drawings, inasmuch as such fastening means is well known in the art and does not form part of the present invention. As illustrated in Figure 2 of the drawings, the soleplate may be provided with a plurality of bosses 18 which are suitably tapped for receiving fastening bolts or studs (not shown).

In a specific embodiment of the invention it is preferred to utilize a so-called "high-wattage" heating element, i. e., 1000 watts or more, which will be capable of providing sufficient heat to compensate for the accelerated heat transfer resulting from the increased ironing rate of which my flatiron is capable.

As shown in Figs. 2 and 4 of the drawings, the heating element indicated at 22 may be encased in insulating material 23 and disposed in a protective metal sheath 24 which is cast within a U-shaped welt 25 extending around the upper portion of the soleplate and spaced from the

outer periphery. Such a disposition of the heating element, it has been found, will effectively produce an even heat throughout the bottom surface of the soleplate.

As mentioned above, the completed flatiron of the present invention provides a construction having many unexpected and useful advantages which cannot be predicated on any existing theories of flatiron construction, nor are these advantages merely additive of the various features embodied in the iron, there being an apparent unexpected coaction leading to the novel and highly useful results obtained. Extensive tests have proved that the flatiron of my invention will greatly reduce ironing fatigue and will materially decrease the number of strokes and time required to complete a given ironing work load and, in general, will make ironing easier and faster without any sacrifice of desirable ironing results.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claim is intended to cover all of the generic and specific features of the invention herein described and all statements of the scope of the invention which, as a matter of language, might be said to fall therebetween.

I claim as my invention:

An electric flatiron effective for reducing the time and effort required in hand ironing operations comprising a soleplate having a flat bottom ironing surface of generally teardrop shape formed with a substantially semi-circular heel portion and with parti-circular side edges which form a gradually curved continuation of the edge of the heel portion, said side edges having a radius of curvature of approximately three times that of the heel portion, said soleplate being formed with an edge surface which is inclined inwardly and upwardly from the plane of the bottom ironing surface at a small angle in the range of 30 to 40 degrees throughout the entire periphery of the soleplate and said soleplate having an upper surface defined by a relatively thick outer edge portion generally similar in configuration to that of the lower ironing surface but inset and spaced inwardly therefrom to form, in combination with said inclined edge surface, a wide, flared and skirt-like bevel extending entirely about the soleplate, and an inwardly tapering shell mounted upon the upper surface of the soleplate and within the periphery thereof with the bevel projecting widely therefrom, rendering the flared bevel and periphery of the soleplate easily visible to the user.

WILLIAM J. RUSSELL.
